UNITED STATES PATENT OFFICE.

ANDREW WALLACE, OF SOUTH CHICAGO, ILLINOIS.

GRAIN-DOOR OPENER.

Specification of Letters Patent. Patented Sept. 5, 1916.

1,197,144.

Application filed September 2, 1915. Serial No. 48,651.

To all whom it may concern:

Be it known that I, ANDREW WALLACE, a citizen of the United States, residing at South Chicago, in the county of Cook and State of Illinois, have invented a certain new and useful Improvement in Grain-Door Openers, of which the following is a specification.

My invention relates to improvements in grain door openers, and has for one object to provide means for quickly and easily opening the grain doors of freight cars and the like.

Another object is to provide means for opening such doors without destroying them.

Other objects of my invention will appear in the specification.

The invention is illustrated more or less diagrammatically in the accompanying drawings, wherein—

Figure 1 shows a cross section through a freight car showing my device in elevation. Fig. 2 is a section along the line 2—2 of Fig. 1. Fig. 3 is a detail on an enlarged scale, showing my device in elevation of a grain door in section with the parts viewed a short interval later in operation than in Fig. 1. Fig. 4 is a section along the line 4—4 of Fig. 1. Fig. 5 is a front elevation of the door contacting portion. Fig. 6 is a section along the line 6—6 of Fig. 5.

Like parts are indicated by similar letters throughout all the parts.

A is the floor, and A¹ the wall of the grain handling house, into which the freight car A² comes riding along the track A³. The freight car which contains grain or other such material, as indicated at A⁴, has its door closed by a so-called grain door A⁵, made up of a series of planks horizontally disposed on edge, extending across the door and nailed or otherwise suitably attached to the inside wall of the car on either side of the door. These planks are normally put in place and nailed or locked in position before the car is filled, and they making a close snug contact with the wall of the car, prevent discharge of material from the car. However, when the car is to be unloaded, the pressure of the material on these boards prevents their being withdrawn, because they must be forced back into the car to release the nails which hold them. The ordinary practice is to cut or chop or break out the bottom two or three boards, thus de-

stroying them. The material then runs out beneath the boards until it sinks low enough so that the operator can climb in over, draw out the nails, and remove the other boards one at a time. This is manifestly an exceedingly expensive process, because these doors cost in the neighborhood of fifty cents to one dollar apiece, and about one third of each door is normally destroyed in unloading. In my arrangement I provide means for forcing the doors into the car against the weight of material, thus drawing out the nails. The door is then drawn up on the inside of the car, so as to permit the material to flow out beneath. The forcing end process and withdrawal of the door takes place almost instantaneously, and no breakage takes place.

B, B are pillow blocks on the floor of the house. They carry rotatably mounted therein a shaft B¹. On this shaft adjacent either end and adjacent the two end pillow blocks B, are sleeves B², having flat supporting surfaces B³, upon which are bolted the two T rails B⁴, B⁴. These two T rails are arranged side by side, one arranged at each end of the shaft. These rails are bent, as indicated at B⁵, at a point slightly above their pivot point, and then extend up to rest against the stop rail B⁶, when in the inoperative position. B⁷, B⁷, are two A-shaped brackets projecting outwardly from the wall A¹. They support at their outer end a cross bar B⁸, upon which are mounted two sheaves B⁹, B⁹, in front of respectively the two T rail beam groups B⁴, B⁴. B¹⁰ is a reinforcing channel riveted to the bases of the four T rails to hold the two beams in fixed position with respect to one another.

C is a motor mounted on a bracket C¹, on the channel B¹⁰. This motor has a pinion C² driving a gear C³ on the shaft C⁴. This shaft is mounted in bearings C⁵ on the bracket C¹ and channel B¹⁰, and carries a pinion C⁶ in mesh with the gear C⁷, which gear in turn is carried by a shaft C⁸ in bearings C⁹ supported on the channel B¹⁰. This shaft is always in operation being driven by the motor, and serves as the counter shaft from which the drive is taken.

D is a miter pinion rigidly connected to a female member D¹ in opposition to a male clutch member D², splined on the shaft.

D³ is a clutch control rod to throw this clutch into and out of operation to rotate or release the miter gear in response to the ro-

tation of the shaft. This miter pinion D is in mesh with a miter gear D⁴ on the worm shaft D⁵. The worm D⁶ on the shaft is in mesh with the worm wheel D⁷ on the drum shaft D⁸. The drum shaft D⁸ is supported on the rail beams, and carries at either end drums D⁹. A cable D¹⁰ is anchored at one end on the drum D⁹, at the other end on a pin D¹¹ between the rails, the bight passing around the sheave B⁹, so that a rotation of the drums winds up the cables and draws the upper ends of the beams out, rotating them about their pivotal point.

E is a miter pinion floating on the shaft 15 C⁸, having a female clutch member E¹ in opposition to a male clutch member E² splined on the shaft, and controlled by a clutch lever E³. This pinion is in mesh with the gear E⁴, which drives a worm shaft E⁵, and by means of a worm E⁶ drives a worm wheel E⁷. This worm wheel is mounted on the hoisting shaft E⁸. It carries at either end the drums E⁹ around which are wound the hoisting cables E¹⁰.

20 F, F, are vertically disposed rails tied together by the cross bars F¹ to form a door opening plunger. The links F², F² are slidably mounted at one end between the rails B⁴ and rest against the stops F³ at their other ends. They are pivoted between the rails F, so as to support the upper end of the door opening plunger pivotally from the main rail beams.

F³ are racks pivoted on the lower ends of 25 the rails F, and in engagement with the gears F⁴ in yokes F⁵ mounted on the rails B⁴. Dogs F⁶ lock the gears against rotation, but may be withdrawn when necessary, to permit rotation of the gears by the hand 30 of the operator to move the rack longitudinally. These dogs engage, of course, one of each of a pair of ratchet wheels F⁷, F⁷, to lock the gear against movement in either direction. The rails are cut away 35 as indicated at F⁸ to permit movement of the rack both longitudinally and rotative.

G, G are pivotally mounted guide shoes 40 mounted on the lower ends of the rails F, having curved car floor contacting surfaces G¹. They are pivotal at points slightly above the ends of the rail, and counterbalanced by means of weights G², so that they normally hang in the position shown in Fig. 1 projecting forwardly in front of the plunger, but when pressure is brought to bear upon the plunger, they assume the position shown in Fig. 3 contacting the door at the point G³. The position of the parts is such that the operator by feeding forward the rack until the shoe rests upon the car floor and its point just contacts the door, will know the parts are in the proper position, and will then lock them in such position.

45 H, H are lifting hooks mounted on car-

riages H¹, which slide between the rails F, the hooks projecting forwardly in front of the rails a distance such that when the parts are in the position shown in Fig. 1, the hook will be just free to fall without contacting the door surface. This hook is adapted to be lifted and controlled by the cables E¹⁰, which passes over sheaves H² on the rails F, so that a rotation of the drum E⁹ will raise or lower the lifting hook 75 as the case may be.

It will be observed that the point of application of the pressure between the rails B⁴ and the rack is above the pivotal point of the rack on the door opening plunger, so 80 that any pressure upon this plunger caused by the forward movement of the upper end of the rail will not tend to lift the plunger, but will force it firmly against and under the door. This pressure or downward component is partially balanced by the fact that the upper link is inclined in the opposite direction, but at the upper end the pressures are much lower, so that there is still a component left tending to hold the plunger 85 down and prevent its upward withdrawal or forcing by the pressure which forces it in to open the door.

H³ is a hook on the end of a handline H⁴, passing over a pulley H⁵ from the shaft E⁸, 90 which may be used to hold the door in position in coöperation with a cleat H⁶ after the mechanism previously described has opened and raised the door.

H⁷ is a stop for the plunger, whose function is to limit the upper movement of the plunger and hook, so that the door opening plunger may be raised into the inoperative position shown in dotted lines before the car is brought in.

It will be evident that, while I have shown in my drawings an operative device, still many changes might be made in size, shape, and arrangement of parts, without departing from the spirit of my invention.

The use and operation of my invention are as follows:—The freight car which is to be unloaded is now on the track in the position shown: The cars vary somewhat in width, somewhat in height, and somewhat in width of sill. The sliding door is moved back, exposing the grain door which is usually made up of three or four boards fastened together, and nailed to the inside of the door jamb. My apparatus is meanwhile in the position shown in dotted lines in Fig. 3 with the heavy rails resting on the support at the top. The operator manipulates the clutch to unwind the cable and lower the door opening foot or plate into 115 the position shown in Fig. 1. The operator by hand moves the rack in or out as the case may be to bring the curved pivoted shoe to rest upon the door sill with the point touching the door. He 120

- then further releases the cable, permitting the door raising hook to drop down so that it also rests on the sill. With the rack locked in position the operator then 5 manipulates the other clutch to tilt the opening heavy levers forward from above. This brings the door opening shoe into engagement with the pivoted foot in the position shown in Fig. 3. The further movement 10 brings the whole shoe against the door, and a still further movement presses the door in against the material behind it, thus drawing the nails all out evenly and freely without breaking the door or the nail.
- 15 As soon as the door has been pushed in so that the nails are all clear a position is held, but no further movement takes place. The pressure on the door at this time without further movement is no greater than it was 20 before, because the material will have been displaced and will assume a position of rest. The other clutch is then operated to wind up the housing drum, the hooks which extend beneath the door engaging it and 25 sliding it up along the rails forming the door opening shoe. This movement will be continued until the door has been raised a few inches, possibly a foot above the bottom of the car. The grain or material then 30 rushes out. The hook on the cable shown in Fig. 1 will be positioned as shown. As the grain runs out, the hook will ride down on the top of the grain until it passes through the door from below. It can then be fastened to the door or brought up and fastened about the cable, and the door held in 35 position without the use of the rigid ponderous door opening machinery. The whole operation takes but a short time. The door 40 is being forced in almost as soon as the power is applied to my device, thus operating with a minimum of labor and without damaging the car doors in any way. The adjustment by means of the gear and ratchet 45 of the position of the bottom of the door pressing frame results in making the effective length of the link connecting the frame with the lever at the bottom a variable while the length of the link at the top of the 50 frame is a constant. When the frame is lifted up into the inoperative position, it swings about the pivot of the lower link on the lever. The pivot point of the upper link is free to slide and it slides to compensate as indicated in dotted lines in Fig. 55 3, but the pivotal point when in operative position is always below the pivotal point on the frame so that there is never a tendency to throw the pivot point on the lever 60 up instead of down.
- I claim:
1. A grain door opener for railroad cars and the like comprising a pressure frame, means for adjusting this frame into opposition to the grain door, and means for forc-
  - ing such frame forwardly against the door to force the door into the body of the car against the material contained therein. 70
  2. A grain door opener for railroad cars and the like comprising a pressure frame, means for adjusting such frame in position adjacent the grain door, and means for forcing it forwardly against the door to force the door into the car against the material contained therein, and means co-operative 75 with such forcing means for raising the door bodily upward after it has been forced back against the material in the car. 80
  3. A grain door opener for railroad cars and the like comprising a lever pivoted adjacent the door, a pressure frame supported on the lever, means for adjusting the position of the frame with respect to the lever and the door so as to bring the pressure frame into operative relation with the door 85 and means for rotating the lever to push the frame against the door and thus thrust the door inwardly. 90
  4. A grain door opener for railroad cars and the like comprising a lever pivoted adjacent the door, a pressure frame mounted on the lever and means for adjusting the position of the frame with respect to the lever and car door to bring the frame into operative relation with respect to the door, and means for rotating the lever to bring the frame against the door and then force the door inwardly, means carried by the frame for raising the door bodily upward along 95 the frame. 100
  5. A door opening mechanism for grain doors and the like, comprising a pressure frame, a pivoted supporting foot on the bottom thereof, a driving member for thrusting the pressure frame into the door and an adjustable connection between it and the pressure frame. 105
  6. In a grain door opening mechanism having a power lever and an opening frame pivotally connected thereto by a pair of links, means for adjusting the length of one of the links, and means for limiting the movement of the pivotal point of the other link with respect to the lever. 110
  7. In a grain door opening mechanism having a power lever and an opening frame pivotally connected thereto by a pair of links, means for adjusting the length of one of the links, and means for limiting the movement of the pivotal point of the other link with respect to the lever, the end of the second link being free to slide along the lever. 115
  8. A grain door opener comprising a pivoted lever, means for rotating it about its pivot point, a door contacting frame mounted thereon, means for adjusting the position of such frame with respect to the door and locking it in position. 120
  9. A grain door opener comprising a piv-

oted lever, means for rotating it about its pivot point, a door contacting frame mounted thereon, means for adjusting the position of such frame with respect to the door and locking it in position, door raising means carried by such frame.

10. A grain door opener comprising a pivoted lever, means for rotating it about its pivot point, a door contacting frame mounted thereon, means for adjusting the position of such frame with respect to the door and locking it in position, means for swinging said frame into and out of the operative position.

11. A grain door opener comprising a pivoted lever, means for rotating it about its pivot point, a door contacting frame mounted thereon, means for adjusting the position

of such frame with respect to the door and locking it in position, door raising means carried by such frame, means for swinging said frame into and out of the operative position.

12. A grain door opener comprising means for forcing a grain door bodily inwardly into the interior of the car against the pressure of the material behind it, and means for then raising the door upwardly in a vertical path.

In testimony whereof, I affix my signature 30 in the presence of two witnesses this 20th day of August, 1915.

ANDREW WALLACE.
